(57) **CLAIM**

The ornamental design for a wallet card, as shown and described.

DESCRIPTION

FIG. 1 is a front perspective view of a new ornamental wallet card;

FIG. 2 is a front elevation view thereof;

FIG. 3 is a rear elevation view thereof;

FIG. 4 is a left elevation view thereof;

FIG. 5 is a right elevation view thereof;

FIG. 6 is a top plan view thereof; and,

FIG. 7 is a bottom plan view thereof.

The dot-dash broken line(s) in the drawings define the bounds of the claimed design and form no part thereof. The dash-dash broken line(s) in the drawings represent(s) portions of the wallet card, and form no part of the claimed design.

1 Claim, 3 Drawing Sheets
